Jean Otis Reinecke, Chicago, Ill., assignor to Minnesota Mining & Manufacturing Company,
St. Paul, Minn., a corporation of Delaware

Application March 29, 1938, Serial No. 76,159

Term of patent 14 years

To all whom it may concern:

Be it known that I, Jean Otis Reinecke, a citizen of the United States, residing at Chicago, in the county of Cook and State of Illinois, have invented a new, original, and ornamental Design for a Tape Dispenser, of which the following is a specification, reference being had to the accompanying drawing, forming a part thereof.

Fig. 1 is a top plan view of a tape dispenser, showing my new design;

Fig. 2 is a side elevation thereof;

Fig. 3, a front elevation; and

Fig. 4, a rear elevation.

The ornamental design for a tape dispenser, as shown.

JEAN OTIS REINECKE.
